FIG. 2

Inventor
William F. Rust,
By *Maurice Clark*,
Carpenter, for Atty's

UNITED STATES PATENT OFFICE.

WILLIAM F. RUST, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-HANDLING APPARATUS.

1,351,541.

Specification of Letters Patent. Patented Aug. 31, 1920.

Application filed October 4, 1919. Serial No. 328,571.

To all whom it may concern:

Be it known that I, WILLIAM F. RUST, a citizen of the United States, residing in Pittsburgh, in the county of Allegheny and 5 State of Pennsylvania, have invented a new and useful Improvement in Coke-Handling Apparatus, of which the following is a specification.

This invention relates generally to mechanism for handling coke discharged from coke-ovens and has for its essential object the provision of means for efficiently handling the discharged coke, during a breakdown of the conveyer which carries the coke 15 from the coke-wharf to the screening station. It will be understood, however, that the invention is capable of valuable applications other than the specific use here mentioned.

With the above and other objects in view, the invention consists in certain novel arrangements, constructions and combinations of parts hereinafter described in a preferred form and particularly set forth in the claims 25 at the end of the specification.

In the drawings:

Figure 1 is a sectional elevational view of a coke-oven battery and coke-handling mechanism constructed in accordance with 30 the present improvements;

Fig. 2 is a plan view of the same.

In the illustrative embodiment of the invention, the improved coke-handling mechanism is employed in connection with a coke-oven battery of the by-product type, and, for convenience the present description will be confined to this use of the invention. Features of construction of the coke-handling mechanism are however readily susceptible of other uses, for example, in connection with coke-oven batteries of the other types; hence, it is manifest that the scope of the invention is by no means confined to the specific use and specific embodiment 40 herein described.

Referring to the drawings,

There is shown in dotted lines in Fig. 1 and in full lines in Fig. 2, a coke-oven battery 11, said battery being, in the present 45 instance, of the by-product type and embodying in its construction a plurality of coking chambers or ovens arranged side by side and having the usual alternating heating walls having flame flues intermediate 55 adjacent coking chambers. The ends of

each coking chamber or oven are closed by the usual doors, indicated diagrammatically at 12 in Fig. 1 and when a charge within one of the coking chambers has been coked the door of such chamber is opened or removed, and the hot coke is pushed out of the chamber into a quenching-car 13.

The quenching-car 13 runs on a track 14 extending lengthwise in front of the coke side of the oven battery 11, whereby said 60 quenching-car may be moved to position for receiving coke discharged from any one of the series of coking chambers which are located in a row lengthwise of said battery. In accordance with the usual practice, the 65 quenching-car is propelled along its track 14 by means of an electric locomotive 15, and when the said car has received a charge of hot coke from one of the aforesaid coking chambers, it is run to the usual quenching- 70 station, not shown, where the hot mass of freshly discharged coke in the car is flooded with cold water to quench the fire and rapidly cool the coke.

Thence, the quenching-car carries the 80 cooled charge of coke along the track 14 to the preferably downwardly inclined coke-wharf or chute 16, the latter being preferably located in front of the oven battery 11, as shown, and along the track 14. The coke 85 is dumped from the quenching-car 13 onto said coke-wharf 16 and, sliding down the latter, discharges onto a belt conveyer 17 of any approved construction which carries the coke from the wharf to the usual screening 90 station, not shown. The quenching-car serves a large number of coking chambers in a battery of ordinary construction and as it is quite essential that the coke from each chamber be quenched immediately after it 95 is discharged and furthermore, as the car must dump its charge of quenched coke before it can receive a fresh charge of coke for quenching, an important requirement for efficient operation, and in order to save 100 loss of coke, is that provision be made for handling the coke as rapidly as it is dumped from the quenching-car.

Ordinarily the coke is carried to the screening station by the conveyer 17 as rapidly as it is deposited upon the coke-wharf 105 by the quenching-car. In the event, however, of a breakdown of the aforesaid conveyer, the handling of the coke by means of the usual mechanism therefor is a prob- 110

lem presenting serious difficulties, inasmuch as the coke-wharf is necessarily of somewhat restricted capacity so that it would quickly become filled with coke, and, for reasons mentioned above, the quenching-car must discharge its coke as soon as the same is quenched, or as soon thereafter as practicable, in order to receive a fresh charge of coke from a coking chamber. It will be understood that the coke is pushed from the coking chambers of a coke-oven battery systematically and in regular timed sequence.

The present invention obviates the above mentioned problem of coke handling, in the event of a breakdown of the conveyer 17, and provides a means for efficiently handling the coke until the conveyer can be repaired, which handling of the coke is effected without waste and without any interruption whatsoever in the normal operation of discharging the coke from the coking chambers of the coke-oven battery. Located adjacent to the coke-oven battery 11 and preferably extending lengthwise of said battery and along the track 14 of the quenching-car is a coke storage pit or receptacle 18. This pit 18 may be sunk from the ground level in front of the coke-oven battery 11 and is preferably of multiple-oven capacity, *i. e.*, of a capacity for receiving charges of coke from a number of the coking chambers or ovens of the aforesaid battery 11 so that coke may be dumped by the quenching-car 13 into the pit 18 for a period of several hours, if necessary, after a break-down of the conveyer 17. The coke may be discharged by the quenching-car 13, after the quenching operation has been effected, into said pit 18 and may be reclaimed therefrom by any suitable instrumentality. For example, a locomotive crane 19 may run on a track 20, the latter also preferably extending lengthwise of the coke-oven battery 11 and in front of the pit 18, as shown more particularly in Fig. 2, which crane is provided with a grab bucket 21 of any approved construction, whereby the coke may be reclaimed from the pit 18. The grab bucket 21 will be lowered into the pit 18 to receive a charge of coke and will deposit such charge of coke into a hopper 22. The hopper 22 is provided with a feed spout 23 through which the coke may discharge onto a belt conveyer 24. Preferably, said belt conveyer 24 extends along the side of the pit 18 between the latter and the track 20 and is long enough to carry the coke from the hopper 22 to a feed spout 25 which discharges onto the aforesaid conveyer 17 for carrying the coke to the screening station. If desired, the hopper 22 may be mounted on a movable support whereby it may be picked up by the locomotive crane 19 and placed in the most convenient location along the pit. The coke discharged from the quenching-car will of

course not be conveyed to the belt conveyer 17 unless the latter has been restored to good running order and the pit will be of sufficient capacity to receive all of the coke discharged from the quenching-car in a normal 70 oven operation of several hours' duration.

If desired the coke may be loaded by the grab bucket directly from the pit 18 into railroad cars which can be run along on tracks to any convenient point near the locomotive crane. A further advantage resulting from the provision of the pit 18 lies in the fact that special coke may be discharged into it, whereas coke of ordinary quality will be discharged onto the coke-wharf in the usual manner. The special coke may be conveyed to the screening station separately from the ordinary coke as desired and loaded into special cars. Or, for example, this special coke may be intermixed 85 with the regular production of the plant in small quantities as desired.

The invention as herein above set forth is embodied in a particular form of construction but may be variously embodied within 90 the scope of the claims hereinafter made.

I claim:

1. In a coke-handling apparatus, in combination with a coke-oven battery; a quenching-car movable lengthwise of said battery; a coke-wharf positioned adjacent to said battery for receiving freshly quenched coke discharged from said quenching-car; an endless conveyer positioned for receiving and carrying away coke discharged from said coke-wharf; a coke storage pit located adjacent to said battery and also adapted to receive freshly quenched coke discharged from said quenching-car; a hopper in juxtaposition to said coke-pit; means for feeding coke from said pit into said hopper; and another endless coke conveyer leading from said hopper to said first-named conveyer, whereby coke deposited in the hopper may be advanced to said first-named conveyer; substantially as specified.

2. In a coke-handling apparatus, in combination with a coke-oven battery; a quenching-car movable lengthwise of said battery; a coke-wharf positioned adjacent to said battery for receiving freshly-quenched coke discharged from said quenching-car; an endless conveyer positioned for receiving and carrying away coke discharged from said coke-wharf; a coke storage pit located adjacent to said battery and also adapted to receive freshly-quenched coke discharged from said quenching-car; and another endless conveyer for advancing coke from said pit to said first-named conveyer, whereby coke deposited in the pit may be redeposited on the first-named conveyer; substantially as specified.

3. In a coke-handling apparatus, in combination with a coke-oven battery; a quench-

ing-car movable lengthwise of said battery; an endless conveyer having its receiving end positioned adjacent to said battery for carrying away coke discharged from said quenching-car; a coke-storage pit located adjacent to said battery and also adapted to receive coke discharged from said quenching-car; a hopper in juxtaposition with said coke pit; means for feeding coke from said pit into said hopper; and another endless conveyer leading from said hopper to the receiving end of said first-named conveyer, whereby coke deposited in the hopper may be advanced to said first-named conveyer; substantially as specified.

4. In a coke-handling apparatus, in combination with a coke-oven battery; a quenching-car movable lengthwise of said battery; an endless conveyer having its receiving end positioned adjacent to said battery for carrying away coke discharged from said quenching-car; a coke storage pit located adjacent to said battery and adapted to receive coke discharged therefrom; a hopper in juxtaposition with said coke pit; means for feeding coke from said pit into said hopper; and another endless coke-ad-
vancing conveyer connecting said hopper with said first-named conveyer; substan-
tially as specified.

ceive freshly-quenched coke discharged from said quenching-car; and another endless 25 conveyer connecting said pit with said first-named conveyer; substantially as specified.

5. In a coke-handling apparatus, in combination with a coke-oven battery; a coke-wharf positioned adjacent to the battery for receiving coke discharged therefrom; an endless conveyer positioned for receiving and carrying away coke discharged from said coke-wharf; a coke storage pit located adjacent to said battery and also adapted 30 to receive coke discharged therefrom; a hopper in juxtaposition with said coke pit; means for feeding coke from said pit into said hopper; and another endless coke-ad-
vancing conveyer connecting said hopper 35 with said first-named conveyer; substan-
tially as specified.

In testimony whereof I have hereunto set my hand this 25th day of Sept., 1919.

WILLIAM F. RUST.
